UNITED STATES PATENT OFFICE.

MICHAEL A. ROLLMAN, OF MOUNT JOY, PENNSYLVANIA.

ICE-CREAM FREEZER.

Application filed October 6, 1922. Serial No. 592,811.

To all whom it may concern:

Be it known that I, MICHAEL A. ROLLMAN, a citizen of the United States of America, and a resident of Mount Joy, county of Lancaster, and State of Pennsylvania, have invented certain new and useful Improvements in Ice-Cream Freezers, of which the following is a full and clear specification.

This invention has special reference to that type of freezer known as the single-motion freezer, i. e., a freezer in which either the can or the dasher is held stationary while the other is rotated, as more fully hereinafter set forth. It will be understood, however, that certain details of construction are applicable to other types of freezer.

In the drawing—

Fig. 1 is a perspective view of the upper part of the freezer;

Fig. 2 is a vertical sectional view thereof;

Figs. 3 to 11 are detail views hereinafter particularly described.

In the drawing annexed (2 sheets), 15 designates the ice-bucket, upon which is mounted the gearing-bridge 16. The bucket is of sheet metal and the bridge is also of sheet metal with depending flanges 17 along its edges. At the outer end of the bridge, it 20 is supported on the can by two flat lugs 18 which extend through openings in the wall of the bucket, just under the rim-bead, and at the other end the bridge is supported by a single flat lug 19, likewise extending through 25 a slot in the bucket. In removing the bridge from the bucket, the bucket is sprung sufficiently to enable the tang or lug 19 to be slipped out of the slot in the bucket; and in replacing the bridge, the bucket is sprung 30 sufficiently to enable the tang 19 to be sprung into the slot. The tangs 18 and 19 rest on flanges 20 formed by pressing in the metal of the bucket along the lower edge of the slots, these pressed-in shelves or lugs 35 forming a very substantial and inexpensive support for the bridge.

The crank-shaft 21 of the gearing is journaled in two upstanding integral ears 22 formed on the bridge, and on its inner end, just beyond the inner bearing 22, it is provided with a driving-gear 23 which is desirably formed by stamping it out of sheet metal. On the end of the shaft is affixed a

washer 24, which is likewise affixed to the face of the wheel 23 and forms in effect a 55 hub therefor.

The gear 23 meshes with a gear 25 which engages and turns the cream-can 26 through the medium of its cover 27 and an upstanding squared nut-like projection 28 carried 60 by the cover, the gear 25 being centrally dished and provided with a squared central opening for engagement with the squared nut 28. The gear 25 rests upon the upper face of the bridge, and its central dished portion 29 depends through an opening in the bridge far enough to engage the upper end of the nut 28, as stated. This gear 25 is stamped up of sheet metal. The teeth are 65 formed by cutting a row of holes in the sheet-metal disk within its edge, these holes forming radial bars 30 which act as teeth for engagement with the driving-gear 23. This is an inexpensive way of making the gear 25, and it serves equally as well as a 70 cast or cut gear. In making this gear, after cutting the sheet metal into a circular shape, I pass the disk through a stamping machine 75 arranged to cut out every other hole, as shown in Fig. 9; then in another stamping operation I cut out the alternate holes, as shown in dotted lines in Fig. 9; in this way, closely-spaced holes may be formed without distorting the radial bars 30 to any appreciable extent. The central dished portion 80 29 may be stamped up during one of the cutting operations or in a separate operation 85 after the holes are cut.

It will be understood that when the bridge is removed from the bucket, the horizontal 90 gear 25 is thereby disengaged from the can-top nut 28. To confine the wheel 25 to the upper face of the bridge, I provide a shield 31 which is struck up from the bridge-plate 95 and extends over the upper surface of the gear, being provided with a central angular hole for engagement with the angular upper end of the dasher-shaft 32 which projects up through the hole, to thereby hold the dasher 100 against rotation while the bridge is in place. This shield 31 is held down in place by having its free end 33 engaged under the hub 24, the end of the part 33 being rounded so as to fit nicely against the annular surface 105 of the hub. This shield 31 is constituted of the piece of metal that is cut out when the

- hole is formed for the depending hub 29 of the gear 25. After the gear 25 is dropped into place, this shield 31 is bent down into position and its free end 33 is snapped under the hub 24, thus not only properly positioning the shield for the reception of the upper end of the dasher-shaft, but also confining the wheel 25 in place. This is a very simple and inexpensive way of making and assembling these parts, it being the main object of this invention to so simplify the parts and the manner of manufacturing the same that the freezer may be marketed at an extremely low price.
- 15 The nut 28 is provided with a central round hole for the passage of the dasher-shaft. This nut is formed in a special manner with a view of obtaining lightness in weight and reducing the expense of manufacture to a minimum. It consists of a sheet-metal thimble closed at its top and having an external annular bead 34 (Fig. 11) formed on it at a distance from its open end, and an additional internal annular bead 25 35 formed nearer to its open end. The open end of the thimble is inserted down through the hole in the can-top until the edge thereof engages in the bead 35; then, by a pressing operation accomplished by a special tool, 30 the bead 34 is compressed to form a closed flange clamping against the top side of the cover, and the depending edge of the thimble is flared outwardly and clamped against the under face of the cover, thereby forming a 35 rigid connection between the thimble and the cover by a single operation of the tool and without brazing or soldering.
- 40 The dasher-bearing 36 in the bottom of the cream-can is formed and affixed to the bottom in substantially the same manner; that is to say, the beaded upper open end of the thimble is inserted up through the bottom of the can and then, by a pressing action, the open sheet-metal end of the 45 thimble is crushed down upon the upper surface of the can-bottom to thereby solidly clamp the bearing-thimble to the can-bottom in such manner as to avoid the necessity of brazing or soldering.
- 50 As shown especially in Figs. 4 and 5, the can-top is locked to the cream-can by having two depressions 37 formed in its side flanges at opposite points, in position to engage depressions 38 formed in the rim-bead of the 55 cream-can. In this way, I provide in a simple way for locking the top of the cream-can cover to the cream-can so as to enable the cream-can to be rotated through the medium of the cover.
- 60 The cream-can bottom 39 is affixed to the cream-can in a special manner. I first form an inwardly-extending annular open fold 40 in the can body at a distance from its bottom end. I then slip into the bottom end of the can, until it comes against said

annular fold 40, the circular bottom-plate 39, this plate being formed with an annular flange 41 which fits within the body of the can below the bead 40 and terminates short of the bottom edge of the can; then, by a suitable press, curl the bottom edge of the can-body and the flange 41 inwardly and close the fold 40, all the parts being forced tightly together and the free edge of the can-body being curled upwardly against the bottom face of the can-bottom 39. In this way, I form a very rigid bead on the bottom of the can and make a water-tight joint, and at the same time I avoid forming any exterior bead on the can, this latter being an advantage in nesting the cans for shipment. The bottom edge of the ice-bucket, which edge is not shown in my drawing, may be formed in the same manner.

I claim:

1. In an ice cream freezer, a sheet-metal bucket having horizontal slots cut in it underneath its bead, the metal of the bucket below said slots being pressed inwardly to form upwardly-facing holes and supporting lugs, and a gearing-bridge having lugs which extend through said slots and rest on said supporting lugs.

2. In an ice cream freezer, a bridge, a driven gear resting thereon, a driving shaft carrying a driving gear meshing with said driven gear and provided with an annular hub, and a guard or shield for holding the driven gear in place carried by the bridge and extending over the driven gear and engaging under the annular face of said hub.

3. The structure recited in claim 2, said guard or shield being formed integral with the bridge and being provided with an angular hole for the reception of the dasher-shaft and having resilient engagement with said hub.

4. In an ice cream freezer, a driving-shaft carrying a driving-gear, a bridge supporting said driving-shaft, and a driven-gear supported on the bridge and having an angular hole for engagement with the rotary element of the freezer, said driven gear consisting of a disk of sheet metal resting flatwise on the bridge and having its central portion dished downwardly to engage said rotary element.

5. An ice cream freezer in which the driven member of the gearing is provided with an angular opening for engaging a nut on the cream-can top, said nut being provided with a central hole for the passage of the dasher-shaft and being constructed of a sheet-metal thimble having its depending open end clamped in a hole in the can-top.

6. In an ice cream freezer, a cream-can top nut consisting of a hollow thimble having a central hole in its top for the passage of the dasher-shaft and having its lower

open end annularly folded and clamped around the edge of the hole in the can-top to thus rigidly anchor the thimble to the can-top.

5 7. A dasher-bearing for a cream-can consisting of a closed-ended thimble inserted up through a hole in the bottom of the

cream-can and having its upper open end folded down on the inside of the bottom to thus rigidly connect the bearing thimble 10 of the can-bottom.

In testimony whereof I hereunto affix my signature.

MICHAEL A. ROLLMAN.
